CLAIM

The ornamental design for a lighted instrument for placing a dam in the ear canal, as shown and described.

DESCRIPTION

FIG. 1 is a top plan view of a lighted otodam placement tool according to the design;

FIG. 2 is a side elevational view of the design shown in FIG. 1, the opposite side elevational view being a mirror image thereof;

FIG. 3 is a bottom view of the design shown in FIG. 1; FIG. 4 is an enlarged end view of the rear end of the design shown in FIG. 1; and,

FIG. 5 is an enlarged end view of the front end of the design shown in FIG. 1.

The broken lines are directed to unclaimed portions of the design; the broken lines form no part of the claimed design.
